DESIGN FOR A COMBINED OXYGEN MASK AND REBREATHING BAG OR SIMILAR AR- TICLE

Arthur H. Bulbulian, Rochester, Minn.

Application April 20, 1942, Serial No. 106,628

Term of patent 14 years

To all whom it may concern:

Be it known that I, Arthur H. Bulbulian, a citizen of the United States, residing at Rochester, in the county of Olmsted and State of Minnesota, have invented a new, original, and ornamental Design for a Combined Oxygen Mask and Rebreathing Bag or Similar Article, of which the following is a specification, reference being had to the accompanying drawings, forming part of the specification—

Fig. 1 is a top plan view of a combined oxygen

mask and rebreathing bag or similar article showing my new design.

Fig. 2 is a side elevational view thereof.

Fig. 3 is a front elevational view thereof.
Fig. 4 is a rear elevational view thereof, being the reverse of the showing of Fig. 3.

I claim:

The ornamental design for a combined oxygen mask and rebreathing bag or similar article, substantially as shown.

ARTHUR H. BULBULIAN.
